UNITED STATES PATENT OFFICE.

CLARENCE MORTON WHITMAN, OF NEW YORK, N. Y.

DESIGN FOR A BLANKET.

No. 39,978.

Specification for Design.

Patented May 4, 1909.

Application filed March 1, 1909. Serial No. 480,801. Term of patent 7 years.

To all whom it may concern:

Be it known that I, CLARENCE MORTON WHITMAN, a citizen of the United States, and resident of the borough of Manhattan, city, county, and State of New York, have invented a new, original, and ornamental Design for Blankets, of which the following is a specification.

Reference is to be had to the accompanying drawing showing a face view of a blanket with my new design applied thereto.

The design comprises a number of representations of opossums each swinging from a limb of a tree and disposed over the surface

of the blanket together with a number of representations of walking opossums in an upright position near the top and bottom edges of said blanket. The design further comprises two spaced parallel lines extending across the blanket adjacent to the representations of the walking opossums.

I claim:

The ornamental design for a blanket as shown and described.

CLARENCE MORTON WHITMAN.
